UNITED STATES PATENT OFFICE.

DANIEL C. GRIFFIN, OF BURLINGTON, IOWA.

LAUNDRY-HEATER.

SPECIFICATION forming part of Letters Patent No. 259,132, dated June 6, 1882.

Application filed June 1, 1880. (Model.)

To all whom it may concern:

Be it known that I, DANIEL C. GRIFFIN, a citizen of the United States, residing at Burlington, in the county of Des Moines and State 5 of Iowa, have invented certain new and useful Improvements in Laundry-Heaters; and I do hereby declare the following to be a full, clear, and exact description of the same, reference being made to the accompanying drawings, forming a part of this specification, and in which—

Figure 1 represents a side elevation of my improved heater; Fig. 2, a vertical central section; Fig. 3, a side elevation, partly broken 15 away, showing my improved heater when used in connection with a dry-room.

My invention relates to certain new and useful improvements in laundry-heaters, having for its object the heating of sad-irons, steam-boiler, and dry-room from one fire; and to this 20 end the invention consists in novel features of construction and combination and arrangement of parts, all as will be hereinafter fully described, and specifically designated in the 25 claims.

Like letters of reference indicate like parts in the several figures of the drawings.

A represents a fire-box, provided with the usual grate, *a*, and ash-pit *a'*, and *b b'* the usual 30 doors for the fire-box and its ash-pit. The fire-box above the grate has inclined sides *D E*, having exterior surrounding rims, *d e*, for supporting the sad-irons and smoothing or polishing irons.

F represents a vertical tubular boiler, secured to the top and over the fire-box through the medium of the flanges *d' f'* of fire-box and boiler, and bolts and nuts *d'' f''*. This boiler is provided with a series of vertical combustion-flues, *f*, passing up through it and communicating with a conical hood, *G*, mounted on the top of the boiler, and having the smoke-stack *H*, provided with the damper *h*. The boiler is provided with the usual steam-gage, 40 inlet and outlet pipes provided with stop-cocks, and other necessary appendages desired for steam-boilers.

The inclined surfaces *D E* provide a large space for heating sad-irons and smoothing or 45 polishing irons, while at the same time form-

ing good radiators, the lower surface, *E*, being adapted for sad-irons and the upper surface, *D*, for the smoothing or polishing irons. The said surfaces *D E* may be round, or of some angular figure, as a decagon or octagon. 55

I represents a dry-room located above the heater, and which heater is partially inclosed by a surrounding jacket, *J*, which communicates with said dry-room, and by means of which the air as it is heated passes up into 60 said dry-room.

It will be seen that by placing a boiler, *F*, above the fire-box, having inclined sides *D E*, I am enabled to heat with one fire sad and smoothing or polishing irons, and at the same 65 time generate steam for laundry use; and also the boiler *F* augments the radiating-surfaces, affording an improvement for heating the dry-room *I*, when used in connection with the surrounding jacket *J*. 70

Having thus fully described my invention, I do not wish to be understood as claiming broadly a fire-box having inclined surfaces for heating sad-irons; nor a fire-box having a steam-boiler arranged on top thereof, having 75 vertical flue or flues passing up through said boiler and communicating with a smoke-stack; but

What I claim as new, and desire to secure by Letters Patent, is— 80

1. In a laundry-heater, the combination of a fire-box having inclined surfaces *D E* and surrounding rims *d e*, for supporting the sad-irons and smoothing or polishing irons, the steam-boiler *F*, arranged over said fire-box, 85 vertical flue or flues *f*, passing up through said boiler, conical hood *G*, and smoke-stack *H*, substantially in the manner as and for the purpose herein shown and described.

2. In a laundry-heater, the combination, 90 with the fire-box having inclined surfaces and steam-boiler, of the dry-room *I* and jacket *J*, partially inclosing said heater, substantially as and for the purpose herein shown and described.

DANIEL C. GRIFFIN.
